UNITED STATES PATENT OFFICE.

AMOS A. CUSHMAN, OF BUTLER, OHIO.

PAPER-HANGING DEVICE.

1,063,861.

Specification of Letters Patent.

Patented June 3, 1913.

Application filed December 26, 1912. Serial No. 728,685.

To all whom it may concern:

Be it known that I, AMOS A. CUSHMAN, a citizen of the United States, residing at Butler, in the county of Richland and State 5 of Ohio, have invented certain new and useful Improvements in Paper-Hanging Devices, of which the following is a specification.

This invention relates to improvements in 10 paper hanging devices and has for its object to provide a device of this nature which will facilitate the papering of ceilings.

A still further object of the invention resides in the provision of a paper hanging 15 device which will do away with the use of scaffolding and by means of which a person may easily and quickly paper a ceiling without assistance.

The invention also aims to generally improve 20 devices of this nature to render them more simple, durable, and commercially desirable.

With these and other objects in view, as 25 will become more apparent as the description proceeds, the invention consists in certain novel features of construction, combination, and arrangement of parts, as will be hereinafter described and claimed.

For a complete understanding of my invention, reference is to be had to the following description, and accompanying drawings, in which,

Figure 1 is a side elevation of my invention, showing the same supporting a strip 35 of paper, Fig. 2 is a top plan view, and, Fig. 3 is an edge elevation.

Referring in detail to the drawings by numerals, 1 and 2 designate parallel bars across the upper edges of which are secured 40 a plurality of cross pieces 3, said cross pieces being arranged in parallel spaced relationship and positioned within notches formed in said bars. The bars 2 coöperate with the cross pieces 3 to form the head of my device

and it will be noted that the upper surfaces 45 of the cross pieces and the parallel bars lie in the same plane. Outwardly converging handles 4 and 5 are secured between the bars 1 and 2 by means of the bolts 6 and nuts 7. The outer ends of the arms 4 and 5 are 50 crossed, as clearly shown in Fig. 1, and secured to each other by means of a bolt 8 and nut 9.

In using my improved paper hanging device, a strip of paper 10 is first covered upon 55 one side with paste and then placed upon the head of my device and raised to the ceiling, against which it is pressed by means of a long handled brush. The relatively long length of the head piece makes it a very easy 60 matter to properly match the various strips of paper.

It is to be understood that I do not wish to be limited to the exact construction of head piece nor to any particular dimensions, 65 nor do I wish to be limited to the specific construction of handles or arms herein shown and described.

Having thus described my invention, what I claim is:—

A paper hanging device comprising a pair 70 of parallel bars, a plurality of parallel cross pieces secured within notches formed in the upper edges of said bars, the cross pieces extending a considerable distance beyond 75 the outer sides of the parallel bars, a pair of converging arms, means for securing the inner end of each arm to both parallel bars, and means for connecting the outer ends of 80 said arms to each other, the arms forming handles whereby the head may be supported.

In testimony whereof I affix my signature in presence of two witnesses.

AMOS A. CUSHMAN.
